UNITED STATES PATENT OFFICE.

WILLIAM L. GUMPRECHT, OF BROOKLYN, NEW YORK, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,237,895.

Specification of Letters Patent.

Patented Aug. 21, 1917.

Application filed October 12, 1912. Serial No. 725,384.

To all whom it may concern:

Be it known that I, WILLIAM L. GUMPRECHT, a citizen of the United States, residing in Brooklyn, in the county of Kings and State of New York, have invented certain new and useful Improvements in Combined Type-Writing and Computing Machines, of which the following is a specification.

This invention relates to combined type-writing and computing machines and most of its features are especially adapted to be used in machines of the class in which numeral keys on the typewriter are caused to set certain members or pins in the computing mechanism which members are subsequently employed for determining the rotation of the computing wheels.

These pins are usually placed upon bars, one bar for each denomination; and the bars are displaced one after another as the typewriter carriage makes its letter-feeding movements; a dog being connected to the typewriter carriage, and a set of jacks being operated *seriatim* by said dog, the jacks being connected to the corresponding computation pin bars to displace or set the same. When the carriage stands at any point, the computation pin bar of corresponding denomination is displaced or set, and when a numeral key of the typewriter is depressed to print a figure at that point, the corresponding pin is set upon the displaced computation bar. After the pins have been set on all the bars in this manner, a general operator is employed for turning all the dial wheels by means of the set pins.

In certain forms of said combined type-writing and computing machines, the computing mechanism may be silenced by effecting a separation between the dog on the carriage and the set of jacks. This has been done by swinging said dog out of the path of said jacks. This silencing has been arranged to be automatically brought about whenever the case-shifting mechanism of the typewriter is used, so that when upper-case characters are being written no computation will be done. Provision has also been made for causing the tabulator keys and the back-spacing dog to likewise silence said computing mechanism.

According to the present invention, the numeral keys are locked whenever said computing mechanism is silenced by the opera-

tion of the tabulator key or the back-spacing key and during the movement of the shift key to and from its upper-case position. Means may also be provided for locking the computing keys against operation whenever the general operator is in motion, or is in any position other than its normal idle position.

In said combined typewriting and computing machine, the numeral keys are usually arranged to engage swinging dogs, so as to prevent more than one of said keys from being depressed at any one time, and the numeral keys according to the present invention may be locked by swinging a member in between said dogs whenever the connection between the numeral keys and the computing mechanism is silenced. Said member will then lock all the numeral keys against operation in the same manner as any key will lock all the others against operation.

The present invention may likewise include means for silencing the connection between the numeral keys and the computing mechanism whenever the general operator is in any but its normal idle position.

Other features and advantages will hereinafter appear.

In the accompanying drawings,

Figure 1 is a sectional, central, longitudinal view taken from front to rear of an Underwood-Hanson combined typewriting and computing machine, embodying the present improvements in one form.

Fig. 2 is a rear elevation, showing a plurality of selecting dogs on the carriage, one dog being shown in effective position, while another is dropped.

Fig. 3 is a detail, showing the mechanism after locking the numeral keys.

Fig. 4 is a perspective rear view, showing the selecting dog, means for rendering it effective, keys connected to silencing means for said dog, and the locking mechanism for the numeral keys.

Fig. 5 is a side view, showing how the mechanism for silencing a dog operates the key-locking mechanism.

Fig. 6 is a side view of a detail, showing how the key-locking means is controlled by the mechanism in Fig. 5.

The typewriter comprises numeral keys 1 and alphabet keys 2, which depress levers 3

2
to vibrate bell cranks 4; the latter engaging type bars 5 to swing them up to strike against a platen 6 mounted on a carriage 7. The carriage is driven by a spring barrel 8, 5 and its letter-feeding movements are controlled by a rack 9, which meshes with a pinion 10 connected to an escapement wheel 11, whose movements are controlled by dogs 12; said dogs operated by a universal bar 13 which is actuated by heels 14 on the type-bars.

The numeral keys have stems 15 to engage and depress arms 16 on rock-shafts 17, forming parts of linkages 17^a to depress or set 15 computation pins 18 on bars 19, which extend forwardly and rearwardly and have at their forward ends racks 20 to mesh with pinions 21 on computation wheels 22.

The typewriter carriage 7 is connected 20 with means to raise the computation racks or bars 19 *seriatim*, so that when said carriage is in position for writing at any point in a column, the computation bar of the corresponding denomination will be raised; 25 and hence when a numeral key is depressed, to write at said point in the column, the linkage 17^a connected to said key will depress that particular pin 18 on the lifted bar 19 which corresponds to such depressed 30 key.

The pins when depressed are utilized for turning the computation wheels 22; the racks 19 being for this purpose driven by a general operator, which may comprise a 35 handle 23 connected to a shaft 24, on whose ends are fixed segments 25, meshing with idle pinions 26, the latter meshing with racks 27 guided in the opposite sides of the machine. Each rack has an offset arm 28, and 40 these arms are rigidly connected by rear and forward cross-bars 29, 30, disposed just beneath the computation bars 19, so that when any pins 18 are depressed, the rear cross-bar 29 may, when driven forwardly 45 by handle 23, engage the depressed pins 18 and drive their bars 19 forwardly. The racks 20 when thus driven forwardly turn the wheels 22, each to an extent dependent upon the pin depressed. Upon the return of 50 the handle 27 of the general operator, the forward cross-bar 30 engages shoulders 31 upon said computation bars, to return them rearwardly to normal positions.

The lifting of the bars 19 to bring their 55 pins within range of the key-operated linkages 17^a is effected by the letter-feeding carriage 7 of the typewriter. Upon the rear of the carriage is mounted a dog or tappet 32, to engage jacks 33, pivoted at 34 upon 60 a bracket and at their rear ends adapted to depress links 35, whose lower ends are pivoted at 36 to levers 37. These levers are adapted to operate linkages 38 to lift the rear portions of the computation bars 19; 65 these linkages forming a denomination-

transposing device as usual in said Underwood-Hanson machine.

Each of the dogs 32 (of which several may be employed) is pivoted at 39 upon a block or carrier 40, which is swiveled upon, 70 and adjustable along a rod 41 fixed upon the carriage, and has a tooth 42 to lock into any of a series of notches 43 formed at letter-space intervals in a rod 44, also fixed upon the carriage. By swinging the carrier 40 up free of the rod or rack 44, the block 40 may be adjusted along said rod 44 and then reengaged with the notches therein.

The platen 6 is usually mounted upon a frame 45, which can shift up and down for writing upper-case and lower-case characters. Normally the lower-case types 46 strike the platen, but when the latter is shifted up, the upper-case characters 47 make the impressions. The figure types are 80 included in the lower-case set 46; but when the capital shift key 48 is depressed, it is not desired to have any of the computing mechanism operate, as figures are not provided in the upper-case set of types 47. 85

The following mechanism is connected to the platen-shifting devices for silencing the selecting dog 32 at this time. The platen frame 45 is usually mounted on a pair of arms 49 hinged upon the carriage frame 7, 90 and a rail 50 is employed for lifting the platen frame, the latter having a roll 51 to run upon said rail. Rail 50 is mounted upon a frame 52, which is operated by a key lever 53, said lever bearing the key 48; 100 and this frame also usually comprises a rock shaft 54 connecting its ends. Extending rearwardly from this rock shaft is an arm 55, having on its rear end a roll 56 to engage a cam arm 57 which depends from a rock-shaft 58. Supporting arms 59 extend up from said rock-shaft 58, and carry at their top a roll 60 which roll supports the dog carrier, and so forms a removable support for a roll 61 on said dog-carrier 40. The 110 normal position of the parts will be seen at Fig. 1, in which the dog 32 and its carrier 40 are held in effective elevated positions by the roll 60.

When the platen 6 is shifted up, the arms 115 59 are brought back, and permit the carrier 40 to drop, together with the dog 32, so that the latter drops below the jacks 33 and cannot operate the latter. A spring 61^a holds the rock-shaft 58 in its normal position to 120 support the dog 32 in its elevated position. The dog-releasing or silencing roll 60 should be of a length equal to or greater than the width of the set of jacks 33 (see Fig. 2), so as to hold the dog in elevated effective 125 position during the time that the dog 32 is traversing the set of jacks. At each end the releaser-roll 60 is provided with a cam, which may be in the form of a coned end 62 formed upon the roll. This cone serves to 130

cam the carrier upwardly to effective position during the run of the carriage, if the releaser-roll 60 is in normal Fig. 1 position. The dog-roll 61 is preferably pointed or coned, as shown to facilitate operation thereon of the releaser-roll 60. It will be understood that the releaser-roll does not need to rotate in all cases, nor is it always necessary to make an anti-friction roll on the dog-carrier 40. By reason of the cam connection at 56, 57 it will be seen that it is possible to effect the releasing operation of the rock-shaft 58 without disturbing the arm 55, or the case-shifting mechanism to 15 which it is connected.

Said Underwood typewriting machine usually is provided with a tabulating mechanism including a set of tabulating keys 63 and levers 64, fulcrumed at 65 and at their 20 rear ends connected to raise decimal stops 66, which coöperate with column stops 67 on the carriage. Upon each of the decimal stops is formed a shoulder 68. These shoulders move the releaser roll to ineffective position 25 when elevated, and for this purpose engage a universal bar 69 fixed upon a rock-shaft 70, from which extends an arm 71, having a pin 72 extending within a slot 73 in a link 74, whose upper end is pivoted at 30 to an arm 76, extending rearwardly from said rock-shaft 58, so that whenever any decimal stop is lifted by its key 63, the releaser-roll or member 60 will be rocked backwardly to permit the dog-carrier 40 to 35 drop, thus preventing the rapid movement of the carriage from effecting injury to the dog 32 or the jacks.

From the rock-shaft 70 extends the usual carriage releasing arm 70^a which is connected by an upstanding link 77 to a lever 78, which carries at its opposite end a roll 79 to take under the carriage-feeding rack 9, and release the same from the control of the letter-feeding dogs, and permit it to run 45 rapidly under the influence of its spring 8.

The carrier 40 is adjusted to a position to correspond with the position of the column stop 67 on the paper carriage 7, and notwithstanding the fact that the tabulator key 50 63 silences dog 32, still it is true that upon the release of the tabulating key and the camming up of the carrier 40 by member 60, said dog 32 will engage and raise the overlying jack 33, so that the release of said 55 tabulator key occasions the raising of one of the computation-pin bars 19 to effective position for the setting of a pin thereon by a numeral key. The slot 73 in the link 74 permits the rock-shaft 58 to be operated independently of the tabulator mechanism.

There is usually provided upon said Underwood typewriter, a back-spacing mechanism, a portion of which is seen at Fig. 4, said portion consisting of a key 80 and a part of a lever 81, upon which said key is

mounted. From the stem of said key projects a pin 82, which overlies the forwardly-extending portion 83 of lever 53, so that whenever the back-spacing key is operated, the shift-key is also depressed, and hence 70 the mechanism is set in motion which swings the releaser-roll 60 back, to permit the dog 32 to drop. At this operation the case-shift mechanism shifts idly; but the carriage is set back a single letter-space, and 75 upon the release of the back-spacing key 80, the dog 32 will lift the corresponding jack 33.

The pivoting of the dog at 39 permits the latter to slip idly past the jacks during the 80 return of the carriage. Owing to the pivoting of the dog at 39, there occurs considerable of the return motion of the carriage before said dog slips past the first jack at the right, Fig. 2. The back-spacing key does 85 not step the carriage back so far, but the provision of the pin 82 on the back-spacing key permits the dog to drop out of effective position and so maintain its upright position as seen in dotted lines at Fig. 2, while 90 traversing the set of jacks; and upon release of said key 80, said dog will lift the overlying jack, and hence this advantage in prior apparatus, arising from pivoting the dog at 39, is overcome. 95

The Underwood-Hanson machine usually comprises means for preventing the simultaneous depression of more than one numeral key, and said mechanism comprises a series of pivoted dogs 85, as seen in Figs. 100 3 and 4, between which dogs the pendants 86 on the numeral keys 1 are arranged to pass as each numeral key is depressed. Said dogs, as shown in Fig. 3, are spaced slightly apart, and the throw of said dogs is limited 105 by abutments in the form of screws 87, there being one abutment at each end of the series of dogs. Said dogs by being spaced a little way apart are allowed a little throw, and said throw of all the dogs 85 is sufficient to 110 let one of the pendants 86 pass between two dogs, but in so doing it closes the space between all the other dogs, so that no other pendants can then pass between any two other dogs. In this way it becomes impossible to depress any other numeral key. 115

All the numeral keys are arranged to be locked by the dogs every time the releaser-roll 60 moves through a certain part of its angular travel, to swing the dog 32 to ineffective position. For this purpose said releaser-roll is arranged, when swung outwardly a certain distance, to strike with its reduced end 62, the raised portion 115 of a cam surface 89 on a lever 88, so that when said releaser-roll is swung outwardly to the proper extent, said lever 88 will be swung downwardly, and in so doing, connections presently to be described, will raise a member 90 between the backs of 120 125 130

the locking dogs 85. Said member is of the same width as a pendent 86 of a numeral key, and when said member occupies the position seen in Fig. 3, it will prevent the depression of any numeral key. The connections between said lever 88 and member 90 include a rod 91 pivoted at one end to the lever 88, and at its opposite end at 92 to a bell crank 93 pivoted on the frame of the machine. The other arm of said bell crank 93 is pivoted to a cross-bar 94 on a link 94 extending forwardly to a rock-arm 95 carrying a pin 96, which rides in a slot 97 in said link, so that when said link 94 is drawn rearward it swings the rock-arm 95 and turns rock-shaft 98 and with it rock-arm 99. Thus, a spring 100 on said rock-arm 99 extending to said member 90 draws it upwardly into locking position whenever the releaser-roll 60 is swung to a position over the cam portion 115. The member 90, it will be seen, swings freely on the rock-shaft 98, and is limited in such swing by abutments 101 and 102 forming the ends of a slot in which said rock-arm 99 passes through the hub of said member 90. It will be seen that if said member 90 is drawn upward to enter between the dogs 85, while a numeral key is depressed, the spring 100 will yield instead of forcing the member between said dogs. This will prevent the catching of a key by jamming between the dogs.

Two of the jacks correspond respectively to the decimal point between dimes and dollars, and to the comma between hundred thousands and millions. These are connected to operate the member 90 by bell cranks 93 identical with the bell crank 93 which is operated by link 19, so that the numeral keys are locked thereby when the comma and the period should be written.

A connection is also provided between the general operator and the computing mechanism, so that unless said general operator is resting in its normal idle position, the connection between the dog 32 and the jacks 33 is silenced. For this purpose there is formed in one of the racks 27 of the general operator, a notch 103, in which normally rests idly an elbow arm 104 pivoted in the frame of the computing mechanism and carrying a bell crank arm 105, which is arranged, through connections to be described later, to swing the releaser-roll 60 to silencing position. The connections between the bell crank arm 105 and said releaser-roll 60 include a bar 106 riding on an idle rock-arm 107 at the forward end of the machine and carrying a depending arm 108 fast on it, which is arranged to be struck by said bell crank arm 105 whenever the general operator moves forward in carrying the number recorded in the computation racks 19 into the computing wheels.

When it so moves forward, the elbow arm 104 rides out of the notch 103, and causes bell crank arm 105 to strike against the arm 108, and move the bar 106 rearwardly, so that the pivot 109 on its rear end, on bell crank 110 will swing up the other arm 111 of said bell crank, and a roll 112 pivoted thereon will swing an arm 113 fast on the shaft 58 on which the silencing roll 60 is carried by rock-arms 59. The arm 111 of bell crank 110 is normally held downward by means of a spring 114 encircling the shaft on which it is pivoted.

The cam 89 which controls the numeral key-locks is extended to have a short flat raised portion 115 on which the releaser-roll 60 rides when the platen is partly shifted to its upper-case position. When, however, the platen is wholly shifted upward, the releaser-roll 60 reaches a hollow 116 in said cam 89 and thus releases the dogs 85 from the member 90, so that in the upper-case position, the numeral keys are not locked and the platen can receive impressions from them.

In order to cause the connection between the back-spacing key and the platen shift key to lock the numeral keys in the manner described, it is necessary to provide, in the present form of the invention, that the back-space key in shifting the platen shall shift it part way only to the upper-case position, so that the releaser-roll 60 will occupy its intermediate position over the raised flat portion 115 of the cam 89. For this purpose, the pin 82, which is arranged to catch the forwardly extending arm 83 of the shift key is arranged to strike said arm only after said back-space key has been part way depressed. In this way the back-space key only shifts the platen part way to its upper-case position. Said shifting is enough to silence the connection between the dog 32 and the jacks 33, but is not sufficient to unlock the numeral key dogs 85 after locking them by means of the raised flat part 115 on the cam 89.

The arm 88 with its cam 89 is held so that releaser-roll 60 will strike it, by a spring 117 which swings rock-shaft 98 by an arm 118 fast thereon; said spring being anchored in a lug 119 projecting from the frame 120 carrying the linkages 17.

Variations may be resorted to within the scope of the invention, and portions of the improvements may be used without others.

Having thus described my invention, I claim:

1. The combination of a system of computation devices, a carriage, a dog on said carriage, a set of denomination-selecting jacks for said computation devices mounted on the machine frame and operable in succession by said dog during the travel of the carriage, keys, including numeral keys, for ef- 130

fecting the travel of said carriage, means for automatically effecting separation between the dog and the jacks to prevent operation of the jacks by the dog, and a device connected to be operated by said automatic separating means for locking said numeral keys against operation.

2. In a combined typewriting and computing machine, the combination with computing devices and actuating means therefor, of a traveling carriage including both numeral and other keys for controlling the movements of the carriage, said numeral keys also controlling computation, and said other keys including tabulating and back-spacing keys and said carriage arranged to travel step by step under the control of the said numeral keys so as to co-act with the successive computing devices in denominational order, normally ineffective means to lock the numeral keys against operation, and means common to said other keys and brought into action when any of said other keys is acting on said carriage, to silence said computing devices and to render said locking means effective.

3. The combination of a system of computation devices, a carriage, a dog on said carriage, a set of denomination-selecting jacks of the machine frame and operable in succession by said dog, keys, figure types operated by said keys, a releasing bar on the machine frame, a carrier on which said dog is pivoted, a rod upon said carriage along which said carrier is adjustable and upon which it may be swung by said releaser bar to silence said dog, and a device for automatically locking said keys when said releasing bar is swung to silence said dog.

4. The combination of a system of computation devices, a carriage, a dog on said carriage, a set of denomination-selecting jacks on the machine frame and operable in succession by said dog, keys, figure types operated by said keys, a releasing bar on the machine frame, a carrier on which said dog is pivoted, a rod upon said carriage along which said carrier is adjustable and upon which it may be swung by said releaser bar to silence said dog, means for locking said keys when said releasing bar is swung to silence said dog, and a connection between said locking means and said releasing bar whereby when said releaser bar silences said dog it may be arranged to occupy one position to lock said keys and another position to unlock said keys.

5. In a combined typewriting and computing machine, the combination with numeral keys and a traveling carriage, of a denomination selector controlled by said carriage, a lock for said numeral keys, and a single means for silencing said denomination-selector and locking said numeral keys.

6. In a combined typewriting and com-

puting machine, the combination with a locking mechanism for preventing the operation of more than one numeral key at a time, of a denomination-selector, means for silencing it, and means controlled by said denomination-selector silencer for locking all said numeral keys by said first-named locking means.

7. In a combined typewriting and computing machine, the combination with numeral keys and computing wheels, of a lock for preventing the operation of one numeral key while another is depressed, a shiftable platen, a key for shifting it, and shift-key-controlled means for locking all the numeral keys by said lock.

8. In a computing machine, the combination with numeral keys and computation members in which numbers are registered by said keys, of computation wheels into which said numbers are carried, a general operator movable to carry numbers from said members into said wheels, an arm adjacent said operator, and a bar on said operator holding said arm to effect the locking of said keys while said general operator is moved from its normal position.

9. In a combined typewriting and computing machine, the combination with computing devices, of a traveling carriage and numeral keys, said carriage arranged to travel step by step, under the control of said numeral keys during computation, so as to co-act with the successive computing devices in denominational order, means for silencing the selection of denominational orders by said numeral keys, tabulating mechanism comprising keys for positioning said carriage, and means brought into action by any one of said tabulating keys during the tabulating runs of the carriage for locking said numeral keys against operation, said locking means acting through the medium of said silencing means.

10. The combination of a series of computation devices, a carriage, a dog on said carriage, denomination-selecting means associated with said computing devices mounted on the machine frame and operable by said dog, keys, figure types operated by said keys, a releasing device mounted on the machine frame and extending in the direction of the run of the carriage, means for operating said releasing device to shift the dog away from said selecting means, a case-shift mechanism, a key-locking mechanism, and means connected to said case-shift mechanism to operate said releasing device and to operate said key-locking mechanism.

11. In a combined typewriting and computing machine, the combination with numeral keys, of a series of dogs arranged to prevent the depression of one numeral key while another is depressed, a member arranged to enter between said dogs to pre-

vent the depression of any numeral key, a shaft on which said member is mounted, and a spring arranged to yield if said member is unable to enter between said dogs.

5 12. In a combined typewriting and computing machine, the combination with numeral keys and computing mechanism controlled thereby, of a denominational selecting device carried by said carriage, said carriage

10 arranged to travel step by step, under the control of the numeral keys, to enable said denominational selector to determine denominational orders in said computing mechanism, a back-space key for returning

15 the carriage letter-space intervals, means for silencing said denominational selector, and means for locking said numeral keys, said back-space key acting through the medium of said silencing means to bring said key-

20 locking means into action.

13. The combination, with computing wheels, numeral keys, and computation members in which numbers are registered by said keys; of a device for connecting said

25 keys and computation members together, so as to enable such registration; a general operator for said computation members, to carry numbers so registered into said wheels; locking means for said numeral

30 keys; and means brought into action automatically by a movement of said general operator out of its normal position for simultaneously disconnecting said device and actuating said locking means.

35 14. In a combined typewriting and computing machine, the combination with numeral keys, computation members and computing wheels, of a traveling carriage, means for registering in said computation members

40 numbers written by said keys, a comma key locking jack, a period key locking jack, a general operator for carrying numbers registered in said members into said computing wheels, a locking arm operated by said operator, and a single lock operated by said jacks and arm.

15. The combination of interlocking means, a case shift, a back space, a tabulating, and an operating means, all locking 50 through said interlocking means, and computer-silencing means through which all said means operate.

16. In a combined typewriting and computing machine, the combination with a 55 traveling carriage and numeral keys, of a denominational selector on said traveling carriage, a silencing roll for moving said selector to ineffective position, devices in which the numbers written by said keys are tem-

60 porarily set up, a general operator for carrying the numbers so set up into a totalizer, and a single lock for said numeral keys controlled by said silencing roll for locking said keys during the operation of a tabulating

key, a back-space key, or when the general 65 operator is moved from its normal position.

17. The combination, with a register or totalizer, and actuating means therefor; of numeral keys for controlling the extent of movement of said actuating means; a denomination selector coöoperative with said actuating means; a lock for said numeral keys; and means for simultaneously silencing said selector and operating said lock.

18. The combination, with a register or 75 totalizer, and actuating means therefor; of numeral keys for controlling the extent of movement of said actuating means; a denomination selector coöoperative with said actuating means; a lock for said numeral 80 keys; means for silencing said selector; and means operated automatically by the silencing of said selector for bringing said lock into action.

19. In a combined typewriting and computing machine the combination with numeral keys, of a lock for said numeral keys, a denomination selector, and means for making said lock effective by moving said denomination selector to ineffective position. 90

20. In a combined typewriting and computing machine, the combination with numeral keys, of a lock for said numeral keys, a denomination selector, means for making said lock effective by moving said denomination selector to ineffective position, and means for releasing said lock while moving said selector still farther from effective position.

21. In a combined typewriting and computing machine, the combination with a carriage and keys including numeral keys, for controlling the step by step movement of the carriage of a lock for said numeral keys, preventing operation of one of said numeral keys when another is depressed, case-shift mechanism and means brought into action automatically by the operation of said case-shift mechanism for actuating said lock to prevent computation while said case-shift mechanism is in action.

22. In a combined typewriting and computing machine, the combination with a carriage, of computing mechanism and numeral keys controlling the same, a lock for preventing operation of any numeral key while another is depressed, a back-space key for shifting said carriage letter-space intervals in a rearward direction, and means for locking all of the numeral keys by said lock, brought into action by the operation of said back-spacing key.

23. A computing typewriter combining a typewriter carriage, step-by-step traversing mechanism therefor, a computer for registering items, numeral keys for printing the items and causing the registration thereof and controlling the traverse of said carriage

5 by said traversing mechanism, a back-spacing key for said carriage, and means controlled by said back spacing key for locking the numeral keys against operation and simultaneously silencing the computer.

6 24. A computing typewriter combining a typewriter carriage, step-by-step traversing mechanism therefor a computer for registering items, numeral keys for printing the 10 items and causing the registration thereof and controlling the traverse of said carriage by said traversing mechanism, a tabulating key for said carriage, and means controlled by said key for locking the numeral keys 15 against operation and simultaneously silencing the computer.

7 25. A computing typewriter combining a typewriter carriage, a computer for registering items, numeral keys for printing the 20 items and causing the registration thereof and causing a letter-feeding traverse of said carriage, a shift-key for causing the numeral keys to print characters other than numerals, means for silencing the computer automatically 25 by the operation of the shift-key, and shift-key-controlled means for locking the numeral keys against operation during the movement of the shift-key and for releasing the numeral keys when the shift-key is in 30 either of its operating positions.

8 26. In a combined typewriting and computing machine, the combination, with a set of computing wheels, and actuating means therefor; of a movable carriage; keys, including both numeral and other keys, for controlling the various movements of the carriage, said numeral keys also controlling the extent of movement of said actuating means; a denomination selector for connecting the numeral keys with said actuating means; locking means for said numeral keys; and means operable automatically by the actuation of one of the other keys for disconnecting said selector and simultaneously bringing said locking means into action.

9 27. In a combined typewriting and computing machine, the combination, with a set of computing wheels, and actuating means therefor; of a movable carriage; keys, including both numeral and other keys, for controlling the various movements of the carriage, said numeral keys also controlling the extent of movement of said actuating means; a denomination selector for connecting the numeral keys with said actuating means, comprising a shiftable member for governing the effectiveness of said selector; locking means for said numeral keys; and means operable automatically by the actuation of one of the other keys for shifting said governing member into ineffective position, so as to disconnect the selector, and simultaneously bringing said locking means 65 into action.

10 28. In a combined typewriting and computing machine, the combination, with a set of computing wheels, and actuating means therefor; of a movable carriage; keys, including both numeral and other keys, for controlling the various movements of the carriage, said numeral keys also controlling the extent of movement of said actuating means; a denomination selector for connecting the numeral keys with said actuating means, comprising a shiftable member for governing the effectiveness of said selector; locking means for said numeral keys; means connected to actuate said locking means; means operable automatically by the actuation of one of the other keys for shifting said governing member into ineffective position, so as to disconnect the selector; and means operated by said governing member during such movement for bringing the actuating means for the locking means into action.

11 29. In a combined typewriting and computing machine, the combination, with a set of computing wheels, and actuating means therefor; of a movable carriage; keys, including both numeral and other keys, for controlling the various movements of the carriage, said numeral keys also controlling the extent of movement of said actuating means; a denomination selector for connecting the numeral keys with said actuating means, comprising a shiftable member for governing the effectiveness of said selector; locking means for said numeral keys; and means operable automatically by the actuation of one of the other keys for shifting said governing member into ineffective position, so as to disconnect the selector, said member being arranged to initially actuate and subsequently release said locking means during said shifting movement.

12 30. In a combined typewriting and computing machine, the combination, with a set of computing wheels, and actuating means therefor; of a movable carriage; keys, including both numeral and other keys, for controlling the various movements of the carriage, said numeral keys also controlling the extent of movement of said actuating means; a denomination selector for connecting the numeral keys with said actuating means, comprising a shiftable member for governing the effectiveness of said selector; locking means for said numeral keys; means operable automatically by the actuation of one of the other keys for shifting said governing member into ineffective position, so as to disconnect the selector; a lever operated by said governing member during said shifting movement; and connections between said lever and said locking means for actuating the latter when the former is so actuated.

13 31. In a combined typewriting and computing machine, the combination, with a set

8
of computing wheels, and actuating means therefor; of a movable carriage; keys, including both numeral and other keys, for controlling the various movements of the carriage, said numeral keys also controlling the extent of movement of said actuating means; a denomination selector for connecting the numeral keys with said actuating means, comprising a shiftable member for governing the effectiveness of said selector; locking means for said numeral keys; means operable automatically by the actuation of one of the other keys for shifting said governing member into ineffective position, so

as to disconnect the selector; a lever arranged in the path of said governing member and arranged to be engaged and operated by the same during said shifting movement; and connections between said lever and said locking means for actuating the latter from the former, said lever having front and rear cam portions for successively causing the actuation and release of said locking means.

WILLIAM L. GUMPRECHT.
